U.S. Cl. D40—5

T1 Q. 3.

T1 Q. 4.

T1 Q. 5.

FIG. 1 is a right front perspective view of a cab for earth moving and handling machinery or the like showing my new design;

FIG. 2 is a left rear perspective view thereof;

FIG. 3 is a top plan view thereof;

FIG. 4 is a left side elevational view thereof; and

FIG. 5 is a bottom plan view thereof.

I claim:

The ornamental design for a cab for earth moving and handling machinery or the like, substantially as shown.
